UNITED STATES PATENT OFFICE

BORIS COOPER, OF BROOKLYN, NEW YORK

DESIGN FOR A BELT BUCKLE COMBINATION

Application filed June 18, 1931. Serial No. 40,249. Term of patent 3½ years.

To all whom it may concern:

Be it known that I, BORIS COOPER, a citizen of the United States, residing in Brooklyn, county of Kings and State of New York, have invented a new, original, and ornamental Design for Belt Buckle Combination, of which the following is a specification, reference being had to the accompanying drawings, forming part thereof, in which—

I claim:

The ornamental design for a belt buckle combination, as shown.

BORIS COOPER. [L. S.]
